CLOSURE CAP FOR A CONTAINER

Carl F. Schmid, Park Ridge, Ill., assignor to Turtle
Wax, Inc., Chicago, Ill.

Filed Dec. 29, 1970, Ser. No. 26,695

Term of patent 14 years

Int. Cl. D9—07

U.S. Cl. D9—261

FIG. 1

FIG. 3

FIG. 1 is a perspective view of a closure cap for a container showing my new design;

FIG. 2 is an elevational view; and

FIG. 3 is a top plan view thereof.

I claim:

The ornamental design for a closure cap for a container, as shown.
